Des. 183,867
Patented Nov. 4, 1958

183,867

ROLL STAMP DISPENSER OR SIMILAR ARTICLE

Walter J. Wagner, Wyckoff, N. J.

Application January 7, 1957, Serial No. 44,413

Term of patent 14 years

(Cl. D52—2)

FIG. 1

Figure 1 is a perspective view of a roll stamp dispenser or similar article showing my new design.

The roll of stamps shown in broken lines is for illustrative purposes only.

I claim:

The ornamental design for a roll stamp dispenser or similar article, as shown and described,
